UNITED STATES PATENT OFFICE

OWEN E. GRIGSBY, OF PARK RIDGE, ILLINOIS, ASSIGNOR, BY MESNE ASSIGNMENTS, TO
PORCELAIN TILE CORPORATION, OF CHICAGO, ILLINOIS, A CORPORATION OF DELA-
WARE

TILED WALL OR THE LIKE

Application filed March 24, 1930. Serial No. 438,378.

The invention relates to the production of tiled surfaces of the general type disclosed in Patent No. 1,594,614 granted August 3, 1926, to George D. Haines. The construction shown in said patent comprises a foundation sheet to which enameled sheet metal tiles are individually cemented during the formation of the tiled surface.

The object of the present invention is to provide a tile having novel means by which such tile may be accurately positioned relative to the adjoining tile.

This object is attained by providing a tile comprising a ceramic body having an enameled sheet metal face, means formed on the sides of the ceramic body interfitting with complementary means on adjacent tiles, and means forming with corresponding means on adjoining tile a space therebetween in which excess cement from the back of the tiles may be pressed in setting the tiles in place.

In the accompanying drawings:

Figure 1 is a fragmentary view in elevation of a tiled wall embodying the features of the invention.

Fig. 2 is an enlarged elevational view of a portion of such a wall.

Fig. 3 is a horizontal section taken along the line 3—3 of Fig. 2.

Fig. 4 is a perspective view of one of the tiles.

Fig. 5 is an elevational view of portions of a modified form of tile.

Fig. 6 is an elevational view of portions of another modified form of tile.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The invention is adapted for use in connection with interior or exterior walls, floors, wainscoting, fire places, tiled surfaces around

built-in bath tubs, store counters, and the like. The supporting structure or foundation surface to which the tile surface is to be applied is a plane surface 10 of any preferred construction such as brick, hollow clay tile, plaster, concrete, wall board of mineral or fibrous material, or the like.

The preferred form of tile shown in the drawings comprises a ceramic body portion 11 having a centrally located raised portion 12 of lesser area than said body portion. On the face of the raised portion 12 is mounted an enameled sheet metal plate 13 having rearwardly extending flanges 14 along its edges which fit closely over the sides of the raised portion 12 to hold the plate 13 in place.

To locate each tile accurately relatively to the adjoining tiles, the body portion 11 is provided with members 15 projecting from one-half of the sides of the tile while the other half of the sides are provided with notches 16. When two tiles are placed side by side, a projecting member 15 of one fits into the notch 16 of the other and thus accurately positions them relative to each other.

In the step of mounting the tiles on the plane surface 10, the back of the body portion of each tile is coated with cement 20 and the tile set upon the plane surface 10 with its projecting members 15 interfitting with the notches 16 on one-half of the adjoining tiles and its notches 16 interfitting with the projecting members 15 on the other half of the adjoining tiles. Thus, each tile being accurately positioned as to all of the adjoining tiles, the entire tiled surface is uniform in appearance.

While the drawings show square tiles, it is obvious that tiles of other regular shapes could be used in any prearranged plan.

In Figs. 5 and 6, there are shown modified forms of tiles in which provision is made for any excess cement placed on the backs of the tiles in the step of mounting them on the plane surface 10. In Fig. 5, the grooves 17 are formed in the ceramic body portion 11 of each tile, which grooves register with corresponding grooves in adjoining tiles. Thus, when a tile is set upon the plane surface 10 and accurately positioned relative to an ad-

joining tile by means of the projecting member 15 and notch 16, excess cement from the back of the tile will be forced into the spaces formed by the registering grooves 17 as indicated at 21.

In Fig. 6, a space is provided for excess cement by forming the projecting member 18 of less length than the depth of the complementary notch 19 in the adjoining tile. 10 Thus, the projecting member 18 and the notch 19 accurately position the two tiles relative to each other, and also provide space into which excess cement 22 from the back of tiles may be pressed.

15 In finishing the tiled surface, the raised portions 12, having a lesser area than the body portion, form grooves between the adjoining tiles which may be filled with cement 23 in the grouting operation, thus concealing 20 the projecting members and the notches.

I claim as my invention:

1. A tile for a tiled wall or the like comprising, in combination, a ceramic body with a face portion of lesser area than said body, 25 an enameled sheet metal plate mounted on said face portion and having flanges fitting over the edges of said face portion, and means formed on the sides of said body portion adapted to interfit with complementary 30 means on adjoining tiles for accurately positioning said tiles relative to each other, said plate being adapted to form grooves with the plates on adjoining tiles into which grouting is placed to cover over said positioning 35 means.

2. A tiled wall comprising, in combination, a foundation surface, and tiles cemented to said surface, each tile comprising a ceramic body portion having means formed on the edges thereof cooperating with complementary means on adjoining tiles for accurately positioning said tiles relative to each other, a centrally located raised portion of lesser areas than said body portion, and 45 a flanged enameled sheet metal plate mounted on said raised portion, the space between said plates being grouted to cover said positioning means.

3. A tiled wall comprising, in combination, a foundation surface, and tiles cemented to said surface, each tile comprising a ceramic body portion having projecting members formed on the edges thereof cooperating with complementary notches on adjoining tiles for accurately positioning said tiles relative to each other, and having notches forming spaces with the adjoining tiles into which excess cement from the back of said tiles may be pressed, a centrally located 55 raised portion of lesser area than said body portion, and an enameled sheet-metal plate mounted on the face of said raised portion, the space between the raised portions on adjoining tiles being filled with cement.

4. A tile for a tiled wall or the like com-

prising, in combination, a ceramic body with a face portion of lesser area than said body, and havng an enameled sheet metal flanged plate mounted on said face portion with its flanges fitting closely against the sides of 70 said face portion, and means on the sides of said body adapted to form spaces with corresponding means on adjoining tiles into which excess cement from the back of the tiles may be pressed, when the tiles are set, to 75 hold the tiles securely in place, said enameled plate being adapted to form grooves with the adjoining plates for grouting.

5. A tile for a tiled structure comprising, in combination, a ceramic body having a projecting member and a correspondingly shaped notch formed on the edges thereof, and an enameled sheet metal secured to the face of said body, said projecting member being adapted to cooperate with the 80 notch in an adjoining tile for accurately positioning said tiles relative to each other.

6. A tiled structure comprising, in combination, a backing, and tiles cemented to said backing in closely adjacent relation, each tile comprising a ceramic body and an enameled sheet-metal facing secured to said body, said body projecting beyond said facing to form a perimetrical shoulder surrounding said facing, the shoulders of adjacent tiles producing grooves between the adjacent facings.

7. A tile for a tiled wall or the like combination, a ceramic block fashioned to provide a base portion and a face portion of less area than said base portion, and a sheet metal 100 facing secured to said face portion.

8. A tile for a tiled wall or the like comprising, in combination, a ceramic base, and an enameled sheet metal face carried by said base, said face being of less area than said base and having marginal flanges turned toward said base, whereby the flanges and the projecting portions of the base provide one part of a cement-receiving groove.

9. A tiled wall comprising, in combination, tiles each having a face portion and a body oprtion extending beyond the margins of said face portion, and opposed recesses and projections on the body portions of adjacent tiles arranged to interfit for properly locating said tiles relative to and in abutment with each other, abutting parts of said body portions having clearances therebetween to receive cement, said face portions on adjacent tiles together with the extending parts of said body portions providing grooves in which cement is placed in grouting, whereby the interfitting parts and said clearances may be concealed.

In testimony whereof, I have hereunto af- 125 fixed my signature.

OWEN E. GRIGSBY.

CERTIFICATE OF CORRECTION.

Patent No. 1,841,370.

Granted January 19, 1932, to

OWEN E. GRIGSBY

It is hereby certified that error appears in the printed specification of the above numbered patent requiring correction as follows: Page 2, line 44, claim 2, for "areas" read area, and line 47, same claim, for "grounted" read grouted; same page, line 83, claim 5, after "metal" insert plate, and line 112, claim 9, for the misspelled word "oprtion" read portion; and that the said Letters Patent should be read with these corrections therein that the same may conform to the record of the case in the Patent Office.

Signed and sealed this 29th day of March, A. D. 1932.
